UNITED STATES PATENT OFFICE.

EDWARD S. GULICK, OF TAMPA, FLORIDA.

ARCH-SUPPORT.

1,239,738.

Specification of Letters Patent. Patented Dec. 31, 1918.

Application filed April 29, 1918. Serial No. 231,487.

To all whom it may concern:

Be it known that I, EDWARD S. GULICK, a citizen of the United States, residing at Tampa, in the county of Hillsborough and State of Florida, have invented new and useful Improvements in Arch-Supports, of which the following is a specification.

This invention relates to new and useful improvements in arch supporters and the principal object of the invention is to make the device adjustable by simply turning a thumb screw.

Another object of the invention is to provide the device with a base plate to which the arch plate is connected at one end by a rivet and by a movable connection at its other end.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a longitudinal section of the device.

Fig. 2 is a bottom view of the device.

Fig. 3 is a top view.

Fig. 4 is a section on line 4—4 of Fig. 3.

As shown in these views the device is composed of a base plate 1 to which the arch plate 2, which may be of any desired form, is connected at one end by the rivet 3 and at its other end by the rivets 4 engaging the slots 5 formed in said arch plate. 6 indicates a thumb wheel pivoted to the upper

face of the plate 1 and provided with a screw threaded shank 7. 8 indicates a screw threaded socket carried by a plate 9 which is riveted to the arch plate and said socket receives the screw threaded shank 7 so that the arch of the plate 2 may be adjusted in relation to the plate 1 by means of said thumb wheel 6.

It will be understood that the slots 5 will allow movement of one end of the arch plate on the plate 1 to permit this adjustment. As before stated the arch plate may be made to conform to the instep and it may be provided with the slots 10 in one side to make this side flexible. The upper face of the arch plate is covered with a piece of leather or the like 11 which projects beyond the edges of said plate as clearly shown in the drawings.

It is thought from the foregoing description that the advantages and novel features of my invention will be readily apparent.

I desire it to be understood that I may make such changes in the construction and in the combination and arrangement of the several parts, provided that such changes fall within the scope of the appended claims.

What I claim is:

1. A device of the class described comprising a base plate, an arch plate movably connected therewith, a screw threaded socket connected with the under face of said arch plate and a thumb wheel between said plates and carried by said base plate and having a screw threaded shank engaging with said socket.

2. A device of the class described comprising a base plate, an arch plate riveted at one end to the end of the base plate and having slots at the other end, rivets engaging said slots and carried by the base plate, a screw threaded socket connected with the bottom face of said arch plate and a thumb wheel carried by the base plate and having a screw threaded shank engaging said socket.

In testimony whereof I affix my signature.

EDWARD S. GULICK.
